UNITED STATES PATENT OFFICE.

HERBERT E. DOLE AND ORRINGTON S. DE ZARA, OF BOSTON, MASSACHUSETTS, ASSIGNORS OF ONE-THIRD TO JAMES W. NOURBOURN, OF SOMERVILLE, MASSACHUSETTS.

TIME CONTROLLING APPARATUS FOR BURNERS.

1,086,589.

Specification of Letters Patent.

Patented Feb. 10, 1914.

Application filed March 28, 1912. Serial No. 686,769.

To all whom it may concern:

Be it known that we, HERBERT E. DOLE and ORRINGTON S. DE ZARA, citizens of the United States of America, and residents of Boston, in the county of Suffolk and State of Massachusetts, have invented certain new and useful Improvements in Time Controlling Apparatuses for Burners, of which the following is a full, clear, and exact description.

This invention has for its object to provide means for causing the operation of a work member, such as a valve in a gas pipe, at certain predetermined periodic intervals, from a suitable time mechanism, such as a clock movement; whereby at certain predetermined times, that can be changed to suit the user, the work member or valve is operated or opened, and at a later predetermined time, according to adjustment, the member will be again operated, or the valve returned to closed position.

Another object of the invention is to provide an improved arrangement of the adjustable stops or engaging members, that are shiftable according to indications corresponding to the time that it is desired to have the work member operated by the clock movement.

A further object is to provide a construction whereby the clock movement together with the operating means can be readily removed from the work member or valve device for repairs or adjustment, or to facilitate replacement by another clock movement with the connected parts.

Another object of the invention is to provide in such a construction having a clock movement including a mainspring, a spring or motor device that serves to actuate the valve or other work member, and suitable connections between the two springs whereby the act of winding up the mainspring of the clock movement, will result in the other said spring being wound up at the same time.

In the accompanying drawings showing one embodiment of our invention, Figure 1 is a front elevation of the device; Fig. 2 is a vertical section on the line 2—2, Fig. 3; Fig. 3 is a side elevation of the device, with the valve shown in vertical section; and Fig. 4 shows one of the adjustable stops for the

dial. Figs. 5 and 6 are a perspective and a plan view to illustrate the guard detent to be hereinafter referred to.

The invention is shown as applied to an ordinary plug valve in the feed pipe for a gas burner, but it is to be understood that instead of swinging the plug of a valve, other and various forms of work members can be operated, as, for instance, an electric switch can be moved to open and closed position.

Any desired form of a time device or clock movement can be employed, and one is shown in the drawing mounted between a front plate 5 and a rear plate 6, that forms the bearing plate for most of the members of the clock movement; and the latter need not be described further than to state that the spindle 7 may constitute the hour arbor, but preferably is so connected that it will make one rotation in 24 hours, and a dial 8 is shown on this arbor having at one half of the circumference marks from 1 to 12 and a similar arrangement on the other half of the circumference. Adjustable stops are carried by this dial, and while only two are shown, obviously a greater number might be employed; the dial being shown with two slots 9 and 10 that are curved and concentric with the arbor of the dial. In each of the slots is arranged a stud shown in the form of a screw 12 having a head 13 for turning it, and a nut member 14 which is placed on the rear of the dial and engaged by the screw after passing through the slot in the dial.

In order to provide a strong bearing for the head portion of the screw against the dial, we arrange an elongated narrow plate 15 containing an aperture 16, through which the screw projects loosely; the plate being curved corresponding to the curved slot and made slightly wider than the slot; and to prevent the nut turning we provide the nut with a short sleeve 17 that is larger than the slot but which has two sides flattened whereby it can project into the slot and be prevented from turning by the flat sides engaging the opposite walls of the slot. Another screw 13 is arranged at the other slot 10 and constructed in the same manner. At one side in the said plates of the clock movement is mounted a spindle 20 having a trip

arm 21 whose extremity has an inclined face 22 positioned to be engaged by the inwardly projecting portion of the stud 12 as the dial is rotated by the clock movement in the direction of the arrow indicated in Fig. 1, whereby as each of the several studs are brought around to the position of the arm, it will be swung and rock the shaft 20.

At the rear of the clock movement is mounted a swinging lever 23 on a suitable pivot 24, the lever carrying a pin 25 at the top connected with an arm 26 on the rock-shaft 20; by which means the lever is swung in one direction when the stop on the dial 10 engages the trip arm, a coil spring 27 connected between the lever 23 and the frame of the movement serving to retract the lever and to return the arm 21 to normal position to be engaged and swung by the next stud. 15 Another supporting plate 2' is mounted beyond the rear plate 6 and between these two plates is suitably supported a shaft 28, that is connected with a suitable driving spring 29 that when wound up will serve to rotate the shaft 28 and operate the connected work member, such as the valve plug 30.

On the shaft 28 are mounted a number of arms, four arms 31, being shown, that are radial and 90 degrees apart; and these arms 30 form with the said lever 23 an escapement, each of the arms having a pin 32 thereon in position to alternately engage the escapement pins 33 and 34 on the said lever, whereby upon the spring 29 being put under tension that would rotate the arms 31, they will advance in the direction of the arrow indicated in Fig. 2 until pin 32 is arrested by the pin 33.

Upon one of the studs on the dial swinging 40 the stop arm 21, the lever 23 will be swung, and pin 33 will move from under the pin 32, but the other stud 34 which is shown as positioned slightly below the pin 33 will thereupon engage the pin 32 and prevent further 45 movement of the arms 31 and shaft 28; but upon the spring swinging the escapement lever 23 back after the stop pin has passed, the pin 32 will be freed from the pin 34, permitting the arm 31 to be swung around by 50 the said spring for the shaft 28. But by this time the lever 23 has moved back and the pin 33 will engage the pin 32 on the succeeding arm 31; whereby it will be understood that as each of the studs on the dial 55 operate the trip arm, the shaft 28 can be advanced by its spring a distance according to the arrangement of the several arms 31 thereon.

A suitable connection is provided between 60 the arms 31 and the plug 30 of the valve, and the latter is shown provided with a disk 35 having a slot 36, and a pin 37 carried by one of the arms 31 projects into the slot, the shaft 28 being preferably in axial alinement with the plug 30; whereby the plug 30

will be given a quarter turn as each stop on the dial engages the trip arm 22, and hence one stop will serve to open the valve, and the succeeding stop to close the valve, the length of time that the valve remains open 70 being determined by the lapse of time as indicated by the hours on the dial. Means are also provided whereby the clock movement together with the said spring for operating the work device and the escapement, can be 75 easily detached from the valve plug 30 or other work member, which may have the slotted plate 35, and suitable piping and connections are provided forming an upper member 40 and a lower member 41, which latter carries a pair of supporting arms 42 and 43, that engage the bottom of the rear plate 6, preferably by having notches in the arms into which the edge of the plate extends.

At the top of the clock movement it is engaged by a pair of curved resilient arms 44 and 45 secured to the upper member 40 and having notches 46 and 47 in their lower faces respectively, into which projects the 90 upper edge of the said rear plate 6. When thus positioned and secured the clock movement will have the pin 37 projecting into the slotted portion of the disk 35 carried by the valve 30; and it will be manifest that by 95 pressing the spring arms 44 and 45 upward to disengage the plate 36, it can be inclined outward and disengaged from the lower supporting arms 41 and 42 and thereupon removed by outward movement, and another 100 similar device substituted therefor, without the employment of any tools whatever.

As seen in Figs 5 and 6, a detent 50 is provided, supported adjacent the trip lever 21, the same being composed of a bent flat metal 105 plate so formed as to have a spring reaction forwardly of the place of support toward the trip lever provided with a lip 52 to engage over the edge of the trip lever. The free extremity 53 of the spring detent member is curved or inclined to partake of the nature of a cam, and its location is in the path of revolution of the time studs, and more or less concealed and in no way conspicuous behind the dial. This prevents the 110 device being tampered with by malicious or inconsiderate persons who might wish to have the controlling device operate at some time other than the predetermined time for its operation; but it is operable, as proper, 115 when one of the time studs comes around to impingement against the part 53 of the detent and crowds it so that the lip 52 is out of its motion preventing relation to the trip lever.

The notched resilient retaining arms 44 and 45 heretofore mentioned are preferably joined by the part 44' which renders them of united or bow form so that both may be operated simultaneously by finger pressure 120

leaving the other hand free to remove or insert the controlling device in its place of support in relation to the work member.

On the winding arbor 1 of the main spring 5 S, is secured a gear 2, meshing with a gear 3, that engages a gear 4, fast on the spring 29 that operates the work member, as set forth. Consequently, when the key is applied and the main spring is wound, the 10 spring 29 for the work member is simultaneously wound; the same operation that winds the main spring of the clock in the usual manner thus serves to also put the other spring under tension.

15 We claim:—

1. The combination with a clock movement having an hour dial, a pair of studs adjustable on the dial, a spindle carried by the movement, a trip lever fast on the 20 spindle and arranged to be engaged alternately by said studs to rock the spindle, a work engaging member rotatably mounted, means for rotating such member, a series of arms carried by the work member, and each 25 having a pin, and an escapement lever having a pair of adjacent lugs arranged to operate with said pins on the arms respectively, the escapement lever being connected with said spindle and reciprocated upon the 30 spindle being rocked from engagement with said stops.

2. In a device of the character described,

the combination with the trip lever and the dial provided with adjustable time studs and a clock movement for operating the dial, of 35 a spring detent having a member for normally engaging the trip lever and to be forced to disengagement by the coaction therewith of the time stud prior to its coaction with the trip lever.

3. The combination of a clock movement, having a time dial, studs on the dial, a rock shaft, an arm on the rock shaft arranged to engage the studs and be swung as the dial rotates, a lever, means for swinging the lever from said rock shaft, a pair of adjacent studs on the lever, a rotatably mounted work member, a spring for the work member, a set of radial arms on the work member, a pin on each of the radial 50 arms positioned to engage the studs on the lever and arrest the rotation of the work member as advanced by its spring, and to permit the advance of the work member as the lever is oscillated to bring the studs 55 thereon to alternately engage the pins on the arms.

Signed by us at Charlestown, Mass., in presence of two subscribing witnesses.
